CLAIM

I claim the ornamental design for the plant protection circular bag with wire mesh, as shown and described.

DESCRIPTION

FIG. 1 is a top view of a plant protection circular bag with wire mesh showing our new design;

FIG. 2 is a bottom perspective view thereof;

FIG. 3 is a top view thereof;

FIG. 4 is a bottom view thereof;

FIG. 5 is a left side view thereof; and,

FIG. 6 is a right side view thereof.

Any broken or shadow lines included are for the purpose of illustration of the plant protection circular bag with wire mesh and do not form any part of the claimed design.
